UNITED STATES PATENT OFFICE

GEDOR W. ALDEEN, OF ROCKFORD, ILLINOIS, ASSIGNOR TO AMERICAN CABINET HARDWARE CORP., OF ROCKFORD, ILLINOIS, A CORPORATION OF ILLINOIS

HINGE

Application filed December 7, 1929. Serial No. 412,328.

This invention relates generally to a hinge for furniture and more particularly to a means for hinging a movable part to a stationary part of an article of furniture, such as the porcelain-covered drop leaf of a kitchen table or the like in which adjacent surfaces of the parts are of such a nature that to bring them into contact would mar them.

10 The general object of the invention is to provide a new and improved hinge for such parts which prevents adjacent surfaces of the parts from coming into contact during any part of the movement of the latter so 15 that the surfaces will not be marred.

A further object of the invention is to provide a new and improved hinge for such parts which permits adjacent surfaces of the parts to lie in close proximity, both in the beginning and at the end of the movement, whereby a very small gap is left between them and yet actual abutment is prevented.

Another object of the invention is to provide such a hinge which is adapted to be 25 mounted directly on the under or back surfaces of the parts so that it is concealed, and whose parts may be made of sheet metal and are simple and inexpensive to construct.

In pursuance of the above objects, I aim 30 to provide a hinge for a porcelain-covered drop leaf of a table or the like in which the drop leaf is hinged to the stationary top of the table, the drop leaf and the stationary top each comprising a wood filler having 35 porcelain-surfaced sheet metal mounted on the upper surface and edges thereof, said hinge comprising two bracket portions mounted on the under surfaces of the stationary top and drop leaf respectively and 40 having longitudinal slots therein, and two lever portions pivotally attached to each other, each being pivoted to one of said bracket portions and sliding in the slot of the other bracket portion, said hinge preventing 45 the adjacent edges of the stationary top and drop leaf from coming in contact during any part of the movement of the latter.

Other objects and advantages of the invention will be understood from the following detailed description thereof, taken in con-

nection with the accompanying drawings, in which:

Figure 1 is a fragmental vertical section through a table showing the preferred form of my invention with the drop leaf in its 55 raised position.

Figure 2 is a view similar to that shown in Figure 1 except that the drop leaf is lowered.

Figure 3 is a plan view looking up from 60 below the hinge showing it in its raised position.

Figure 4 is a fragmental vertical section through a table showing a modified form of the invention with the drop leaf in its raised 65 position.

Figure 5 is a view similar to that shown in Figure 4 except that the drop leaf is lowered.

Figure 6 is a plan view looking up from 70 below the modified form of the hinge showing it in its raised position.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

In the drawings, a table is shown for which this hinge is suitable. The table comprises 85 a stationary top A and a drop leaf B, the adjacent edges of which are separated. This separation has been slightly exaggerated in the drawings for the sake of clarity in illustration. The top A, and likewise the drop leaf B, comprises a wood filler 11 having porcelain-surfaced sheet metal 12 mounted on the upper surface and edges thereof with the metal forming a fold 13 underneath the wood a short distance to secure it thereto. 90 While it is contemplated that two hinges will be used on each drop leaf, only one has been shown as the other is exactly similar. When these hinges are used on a table, such as is described herein, the table is also provided 95 100

with a pair of supports (not shown) which are adapted to hold the drop leaf in its raised or horizontal position.

The hinge illustrated herein comprises generally two bracket portions or members adapted to be secured to the top A and drop leaf B and two links or lever portions pivoted to each other, each of said links being pivotally attached to one of said bracket portions and slidably attached to the other of said bracket portions, said hinge preventing the adjacent edges of the top A and the drop leaf B from coming in contact during movement of the latter and yet from leaving any gap therebetween of substantial size.

In the present instance, two bracket portions 14 and 14^a are adapted to be secured to the under surfaces of the wood fillers of the top A and drop leaf B respectively beyond the fold 13 of the porcelain-surfaced sheet metal as by screws. Each bracket portion, 14 or 14^a, comprises a strip of sheet metal bent in a right angle, one side of which lies against the wood filler and the other side of which has a longitudinal slot 15, or 15^a, and an inwardly extending lug 16, or 16^a.

As mentioned above, the invention includes two links pivoted to each other. In the present embodiment, the two links 20 and 20^a are pivoted to each other at 21 intermediate their ends. Each link has one end pivotally attached at 22, or 22^a, to the lug 16, or 16^a, on one of the bracket portions and at the other end has a lug 23, or 23^a, bent at a right angle to the link and sliding in the slot 15 of the other bracket portion. To hold the lug 23, or 23^a, in the slot 15, or 15^a, two ears extend from the lug transversely of the slot. The ends of the slots 15 and 15^a are so placed that the abutment of the lugs 23 and 23^a against the ends limits the movement of the drop leaf B from a lowered position in which the drop leaf hangs substantially vertically down from the top A to a horizontal position level with the top.

In the operation of the hinge, the pivot 22 and the slot 15 remain in a fixed position because they form a part of the member 14 fixed to the stationary top. The link 20^a pivots around the pivot 22 and hence the pivot 21 moves in an arc whose center is the pivot 22. The link 20 is then constrained to move in a path determined by the movement of the pivot 21 and the slot 15, the link 20 being translated horizontally because of the effect of the slot, and pivoted about the lug 23 because of the pivot 21. The resultant effect of this movement of the link 20 is that the horizontal component of the movement of the pivot 22^a is equal to the horizontal component of the movement of the pivot 21 and to the horizontal movement of the lug 23, while the vertical component of the movement of the pivot 22^a bears the same ratio to the vertical component of the movement of the pivot 21 as the ratio of the horizontal

distance from the lug 23 to the pivots 22^a and 21, respectively. Thus, the pivot 22^a, which is rigid with the drop leaf, is moved horizontally and is given an exaggerated downward movement which causes the drop leaf to move away from the top during that part of its movement from a position shown in Figure 1 to the position it occupies when the pivot 21 is directly below the pivot 22. During the remainder of the movement of the hinge, pivot 21 is moved up to a position in the same horizontal plane with its original position shown in Figure 1, and the pivot 22^a is correspondingly moved up to the same extent that it was moved down in the first part of the movement. Thus, pivot 22^a lies in the same horizontal plane at the end of its movement that it did at the start of its movement, and its axis is coincident with the axis of the pivot 22.

The link 20^a merely pivots about the pivot 22 and hence the lug 23^a moves from the position horizontally aligned with the pivot 22 to a position vertically aligned with the pivot 22, the slot 15^a having a similar pivotal movement although it may be translated relative to the lug 23^a by the movement of the pivot 22^a.

The position of the drop leaf at any time is determined by the positions of the pivot 22^a and the slot 15^a. The movement of these two having been shown, it follows that, while the drop leaf is being lowered from the position shown in Figure 1 to the position shown in Figure 2, it is moved from a position in which the adjacent edges of the drop leaf and top are in close proximity but not in contact to a position in which the adjacent corners are in close proximity but not in contact and during such movement the drop leaf moves away from the top and back.

In Figures 4, 5 and 6 a modified form of the invention is shown which comprises, as in the other form, two bracket portions 30 and 30^a and two lever portions or links 31 and 31^a. With this form of the hinge, the drop leaf is moved from a horizontal position level with the stationary top to a vertical position under the top and back from the front edge thereof, as shown in Figure 2, and during the movement the adjacent surfaces of the drop leaf and top are kept out of contact.

In the modified form, the bracket portion 30^a is adapted to be secured to the under surface of the wood filler of the drop leaf beyond the fold 13 of the porcelain-surfaced sheet metal as by screws. The bracket portion 30 is similarly secured to the top but farther back from the edge so that the drop leaf when lowered may be positioned between the bracket portion 30 and the edge of the top. The bracket portions are provided with slots 32 and 32^a which slant downwardly away

from their adjacent ends, and have inwardly extending lugs 33 and 33^a.

The two links 31 and 31^a for the modified form comprise triangular pieces of sheet metal with their center portions cut away to lighten them without materially decreasing their strength. They are pivoted together at 34 at corresponding corners and have another corner pivotally attached at 35 and 35^a to the lugs 33 and 33^a, respectively. The third corners of the links are bent to form lugs 36 and 36^a sliding in the slots 32 and 32^a with ears extending transversely of the slots. The abutment of the lugs 36 and 36^a against the ends of the slots 32 and 32^a limits the movement of the drop leaf.

In the operation of the modified form of hinge, the pivot 35 and the slot 32 remain stationary as they are a part of the member 20 of the bracket portion 30 fixed to the top. The link 31^a turns on the pivot 35 and hence the pivot 34 moves in an arc whose center is the pivot 35. Because of this fact, the link 31 is constrained to move in a path determined by the movement of the pivot 34 and the slot 32. The resultant effect of this movement is that the pivot 35^a, which is a part of the link 31, is given a downward movement which causes the drop leaf to move away 30 from the top during the first part of its movement, while the pivot 34 is moved down to its lowest point. During the remainder of the movement the pivot 35^a is moved up and, because of the fact that the slot 32 is slanted 35 downwardly and the lever 31 is thereby rocked about the pivot 34, this movement is still more exaggerated. In this manner the pivot 35^a is moved from a position separated from but in the same horizontal plane as the 40 pivot 35 to a position in which the axis of the two pivots 35 and 35^a coincide.

The link 31 merely pivots about the pivot 35. As a result the lug 36^a correspondingly pivots about the pivot 35, the slot 32^a having 45 a similar pivotal movement although it is translated relative to the lug 36^a because of the movement of the pivot 35^a.

The position of the drop leaf is determined at any time by the position of the pivot 35^a and the slot 32^a. The movement of these two having been shown, it follows that the drop leaf is lowered from the position shown in Figure 1, in which its edge is in close proximity to the edge of the top, to a position in 55 which its edge is in close proximity to the under surface of the top. During this movement the drop leaf is moved away from the top a sufficient distance to permit the edge of the drop leaf to clear the lower corner of 60 the top and then is moved inward and upward so that it is in a vertical position with its edge in close proximity to the top between the bracket member and the edge of the top.

65 It is apparent from the above description that I have provided a new and improved

hinge which prevents adjacent surfaces of the drop leaf and top from coming in contact during any part of the movement of the latter so that the surface will not be marred and yet only a very small gap is left between them so that the hinge is concealed. 70

I claim as my invention:

1. A hinge comprising two members each of which has an attaching portion and a slotted flange, the inner end of said flange extending beyond the inner end of the attaching portion, whereby it will lap a metal covering on the edge of the parts to be connected by the hinge, and a pair of links connecting said members, said links being pivoted to each other and each link being pivoted at one end to the extending end of one flange and having a projection slidably in the slot of the other flange. 75

2. A hinge as in claim 1, the extended end of said flanges being offset laterally to different planes, to lap each other when the hinge is folded, with both of the links located in the spaces between said ends. 85

In testimony whereof, I have hereunto af- 90 fixed my signature.

GEDOR W. ALDEEN.
